SCOOTER BOARD

Samuel S. Mittleburg, New York, and Clifford
Lobel, Brooklyn, N. Y.

Application July 25, 1939, Serial No. 286,306

9 Claims. (Cl. 280—87.05)

This invention relates to new and useful improvements in a scooter.

The invention has for an object the construction of a scooter which is characterized by a board or flat body of wood or metal and a novel arrangement of scooter parts associated therewith.

More specifically the invention proposes the construction of a scooter chassis arranged in a manner so that many portions thereof may be folded up to reduce the compass of the scooter so it may easily be stored in a closet, or corner, or other small place.

Still further the invention proposes the construction of a novel scooter which will be attractive to the general public, and which will create a new sport both for children and grown-ups.

Another object of this invention is to so construct a scooter that it may be provided with various types of extra gadgets to increase its price and to make it a high price item, or it may be constructed without these gadgets to produce a low price article.

Still further the invention proposes a novel construction for the steering mechanism of the scooter, characterized by a handle which is hingedly mounted and which may be folded when desired.

Still further the invention contemplates a novel construction of a seat mounted upon the scooter body and arranged in a way so that it may be folded flat against the scooter body.

Still further the invention proposes the construction of a scooter as mentioned which in its simplest form may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a scooter constructed in accordance with this invention.

Fig. 2 is a plan view of the scooter illustrated in Fig. 1.

Fig. 3 is a fragmentary longitudinal sectional view as though taken on the line 3—3 of Fig. 2, but illustrated with the steering handle hinged closed.

Fig. 4 is a perspective view of a portion of the steering mechanism.

Fig. 5 is a perspective view of an upper plate used in the steering mechanism.

Fig. 6 is a fragmentary elevational view looking in the direction of the line 6—6 of Fig. 4.

Fig. 7 is a fragmentary transverse sectional view taken on the line 7—7 of Fig. 4.

Fig. 8 is a vertical sectional view taken on the line 8—8 of Fig. 7.

Fig. 9 is a fragmentary sectional view taken on the line 9—9 of Fig. 2.

Fig. 10 is a fragmentary enlarged sectional view taken on the line 10—10 of Fig. 1.

Fig. 11 is a perspective view of a scooter constructed in accordance to another embodiment of this invention.

Fig. 11A is a perspective view of one of the traction elements used in Fig. 11.

Fig. 12 is a perspective view of the steering mechanism of another scooter constructed according to another modification of this invention.

Fig. 13 is a perspective view of a scooter constructed according to a still further embodiment of this invention.

Fig. 14 is a vertical sectional view taken on the line 14—14 of Fig. 13.

Fig. 15 is a perspective view of the steering mechanism of another scooter, constructed according to another embodiment of this invention.

The scooter, illustrated in Figs. 1 to 10 inclusive, includes a flat body 15 of wood or metal and having side rails 16 along its sides and bumpers 17 or similar members at its front and rear ends. A disc 18 is axially rotatively mounted on the bottom face of the body 15 in the vicinity of its front end. Traction elements are mounted on the bottom of the disc 18. In the form of the invention illustrated these traction elements comprise wheels 19. These wheels are mounted on brackets 20 which are engaged in holding clamps 21 mounted upon the bottom of the disc 18.

Each of the clamps 21 has its longitudinal edges 21^a bent inwards towards each other forming flanges over which flange portions 20^a of the brackets 20 engage. A lug 22 is formed upon the rear end only of each clamp 21 and extends downward over the edge of the brackets 20 for holding these parts together. The brackets 20 may be removed and replaced with other traction elements of the same design, or other design. Thumb screws 21^c are mounted on the clamps 21 and engage slots 20^c in the flange portions 20^a of the brackets 20 for clamping the brackets fixedly.

on the clamps 21, or other fastening means may be employed.

A member 23 is mounted upon the top face of the disc 18 and extends through an arcuate slot 24 formed in the flat body 15. This member 23 is in the form of an angle member having one arm 23^a attached upon the top face of the disc 18 and having another arm 23^b extending vertically upwards and through the arcuate slot 24. 5 A handle 25 is hingedly mounted on the disc 18 and extends upwards and is adapted for steering the scooter. This handle may be pivoted downwards to a position as illustrated in Fig. 3, substantially flat against the top of the flat body 15. 10

The disc 18 is rotatively supported by an axial fastening element 26 which extends upwards through the flat body 15. A nut or pin 27 engages upon the bottom of the fastening element 26 for releasably holding the disc 18. 15

A reinforcement plate 28, illustrated per se in Fig. 5, is attached by fastening elements 29 to the bottom face of the flat body 15 coaxially with the fastening elements 26. This plate preferably 25 is made from metal. The body 15 preferably is made from wood or metal. The plate is provided with an arcuate slot 30 which is aligned with the arcuate slot 24. A ball bearing 31 is interposed between the edge portions of the disc 18 and the plate 28. The arrangement is such that the ball bearing 31 serves to form the bearing for the turnable disc 18. 30

The handle 25 comprises a tubular strip or member having a transverse top portion 25^a by 35 which it may be held and manipulated. The handle also has side arms 25^b which extend downwards towards the flat body 15. These arms 25^b continue into curved portions 25^c which engage around the edge portions of the flat body 15, and connect with a rod portion 25^d, see Fig. 4, 40 extending across the bottom face of the disc 18. Several brackets 33 are attached upon the bottom face of the disc 18 and serve to turnably support the rod portion 25^d. The arrangement 45 is such that the handle 25 may be pivoted forwards or rearwards using the rod portion 25^d as a pivot. Moreover when the handle 25 is turned it will correspondingly turn the disc 18.

A base arm 34 is hingedly connected with the 50 member 23 and more particularly with the top end of the vertical arm 23^b of this member. A front arm 35 is hingedly connected with the base arm 34 by a pintle, bolt, or rivet 36. The outer end of the front arm 35 has a tubular portion 55 37 which engages around a cross bar 25^e mounted across the side arms 25^b of the handle 25.

A latch is provided for holding the arms 34 and 55 35 in line with each other or permitting these arms to be bent about the pintle 36 as a pivot. 60 This latch includes a leaf spring 38 having a central portion 38^a and side arm portions 38^b. In cross section, the arms 34 and 35 are U-shaped. Moreover these arms are set one into the other as clearly illustrated in Fig. 6. The leaf spring 65 38 is set into the arm 35 and is so arranged that the central portion 38^a is located below the pintle 36. The side arms 38^b extend along the side arm of the arm 35. At their extremities the side arms 38^b are provided with outwardly projecting pins 70 40. Intermediate of their ends the arms 38^b carry short pins 41. These latter pins 41 normally extend through openings in the sides of the arms 35 and 34. In this condition the latch is in its closed position. This position is illustrated in 75 Fig. 6.

When desired the pins 40 may be pressed towards each other so as to flex the side arms 38^b of the leaf spring 38, in a manner to disengage the pins 41 from the sides of the arms 34. Then the arms 34 and 35 may be folded. In Fig. 4; the 5 arms 34, 35 are shown extended so as to hold the handle 25 in an upright position. When the latch is open and the arms 34 and 35 are folded, the handle 25 will be simultaneously moved downwards and the parts will assume positions as 10 illustrated in Fig. 3. In this figure the arm 34 is shown flat against the top face of the flat body 15, the arm 35 is shown extending forwards between the arm 34 of the handle 25, and the handle 25 is shown in a lowered position substantially against the top of the flat body 15. 15

The scooter body 15 is supported at the rear on wheels 44. These wheels are mounted in brackets 20 which in turn are supported on clamps similar to the clamp 21 in Figs. 7 and 8, 20 or are directly attached to the body 15. Skate heel backs 52 may be connected with the clamp 21. These backs 52 then project up through the openings 52' in the body 15.

The scooter is also provided with a braking system so that it may be stopped. The particular brake illustrated comprises a vertical stem 55 slidably engaging through an opening 56 in the flat body 15. A brake shoe 57 is mounted upon the bottom end of the stem 55. A pedal 58 30 is mounted upon the top end of the stem 55. An expansion spring 59 is coaxially mounted on the stem 55 and acts between the pedal 58 and the top of the flat body for normally urging the stem upwards. A collar 60 is mounted on the stem 55 and engages the bottom face of the body 15 for limiting upward motion of the stem. To apply the brake one steps upon the pedal 58 forcing the stem 55 downwards against the action of the spring 59 to the position indicated by the dot and dash line in Fig. 10, and then the brake shoe 59 will engage the ground. In practice various other styles of brakes may be used.

The scooter is also provided with a seat capable of holding several persons and capable of being 45 folded when desired. This seat includes a front member 62 normally extended vertically and at its bottom edge being connected with a hinge 63 mounted upon the top of the body 15, and arranged to hingedly support the back member 64. 50 The back member 64 is formed from tubing material or other material and is arranged to have a top horizontal arm 64^b which may be gripped and manipulated. It also has side arms 64^c, and an intermediate horizontal arm 64^d. 55

A seat proper 66 is mounted between the intermediate horizontal arm 64^d and an intermediate point on the front member 62. A railing 67 is mounted between the back member 64 and the front member 62, which people may grip 60 when seated upon the seat proper 66. Pintles 68 serve to hingedly connect the guide rail 67 to the side arms 64^c. At the front end, the side arms 67 connect with a transverse element 67^a which extends through a tubular portion 62^a formed 65 upon the middle of the front member 62.

A base arm 34' is hingedly connected with an angle member 23 which is mounted on the back portion of the flat body 15. This base arm 34' is associated with a front arm 35', the top of 70 which has a loop portion 37' engaging over transverse bar 64^d. The arms 34' and 35' telescopically engage each other, the front arm 35' engaging into the base arm 34'. A strong spring 34^c is mounted upon the base arm 34' and has its 75

front end engaging through a slot 34^d formed in the base arm 34'. This end of this spring engages one of a plurality of spaced recesses 35^e formed in the front arm 35'. A knob 34^e is mounted on the spring 34^c by which the spring may be flexed to disengage its front end.

When it is desired to fold down the back member 64 it is necessary that the knob 34^e be pulled to disengage the spring 34^c and then the arms 34' and 35' may slide relative to each other. This permits the member 64 to be hinged forwards, substantially flat upon the body 15.

The operation of the device is as follows:

Persons intending to ride the scooter may sit themselves upon the seat 16. One person may stand to the back of the back and hold onto member 64, and another person may stand upon the front portion of the scooter to operate the steering handle and the brakes. The scooter may be propelled manually along the ground or may be driven down hill.

To steer the scooter it is merely necessary that the handle 25 be turned in one direction or the other. This will cause turning of the disc 18. The slots 24 and 30 do not interfere with the turning of the disc 18 since the angle member 23 extends upwards through these slots.

The scooter is folded in the following way, so as to reduce its compass for storing, shipping and other purposes.

The pins 40 of the front arm 35 are pressed together to open the latch. Then the handle 25 may be hinged rearwardly and downwardly. Also the latch of the arms 34' and 35' of the back member 64 is released and the back member 64 may be hinged forwardly or rearwardly. As the back member is so moved the seat 66 and the rail 67 will be moved downwards substantially one upon the other and substantially flat against the top face of the body 15. The front member 62 will hinge, forwards or rearwards and downwards because of the hinge 63. The scooter is now in its folded condition.

In Fig. 11 another embodiment of the invention has been disclosed which distinguishes from the prior form in several respects. In this form of the invention traction elements 19' which are runners for snow and ice, have been substituted for the wheels in the prior form. These traction elements 19' have flange 19'' and are mounted upon clamps 21, see Figs. 7 and 8. Furthermore traction elements 44' in the form of runners have been substituted for the traction elements 44 of the previous form of the invention which were wheels.

The scooter has also been provided with a sail or umbrella 70 mounted upon a mast 71 extended through an opening 72 formed in the seat proper 66. At the lower end of the mast 72 there are radial arms 73 which support side runners 74. The mast 71 may be manually turned for directing the sail as desired into the wind. The mast 71 is formed of an upper section 71^a and a lower section 71^b which are rotatively connected. The lower section 71^b may be turned for turning the radial arms 73 to direct the runners 74 as desired, or the runners 74, may be guided with the feet by the sitter.

A flexible cover 75 is also mounted on the top arm 64^b of the member 64. This cover 75 is shown rolled in an inoperative position. If desired it may be extended and used as a sun shield for some of the riders on the scooter, particularly those seated on the seat proper 66.

In other respects this form of the invention

is identical to the prior and identical parts may be recognized by the same reference numerals.

In Fig. 12 another embodiment of the invention has been disclosed which relates particularly to the steering mechanism of a scooter. According to this form of the invention the steering disc 18 is provided at its top center with a tubular bracket and has a bottom portion 77^a attached to the bottom face of the disc 18 by a bracket 18^c. The steering post 77 is made from two sections hinged together by a pintle 78. The upper sections of the post 77 is engaged by a collar 79 which is hinged to the upper end of the front arm 35 of a mechanism for holding the steering post 77 in an upright position or permitting the post to be hinged downwards. The front arm 35 connects with a base arm 34 which in turn is pivotally connected at its rear end upon the angle member 23. This angle member is mounted upon the top of the disc 18. The connection between the arms 34 and 35 is identical as previously described, on the front handle 25, with the identical latch for these arms being provided.

A steering wheel 82 is pivotally mounted upon the top of the post 77 by a pintle 83. A pair of hinged arms 84 are pivotally connected in their outer ends by pintles 85 and 86 respectively, to the steering wheel 82 of the post 77. This arrangement is such that in the extended position of the arms 84 they pass their dead center and lock the steering wheel 82 in substantially in horizontal position. When the post 77 is folded downwards, as permitted by the arms 34 and 35 then the steering wheel 82 may be hinged to a horizontal position by folding the arms 84 back past their dead centers. To do this it is necessary that the arms 84 be folded together, and then the steering wheel 82 may be hinged on the pintle 83. The upper section 40 of the steering post 77 may be hinged downwards on the pintle 78. This steering unit is intended to be applied to a scooter, as previously described.

In Figs. 13 and 14 another embodiment of the invention has been disclosed which distinguishes from the prior form in the fact that the scooter comprises a flat scooter body 90, supported upon suitable traction elements 91, which in turn are supported on clamps 92 mounted upon the bottom of the scooter body 90. At the front, the scooter is provided with a handle 93 formed from tubular or other material and having a bottom arm 93^a and side arms 93^b. The bottom arm 93^a is hinged to the body 90. The side arms 93^b are pivotally connected with bars 96 which in turn are pivotally connected with other bars 97 in turn pivotally connected with the sides of the flat body 90. The bars 96 and 97 are capable of passing a dead center and then 60 maintain extended positions. A cross head 93^c is mounted across the upper ends of said arms 93^b.

The arrangement is such that the bars 96 and 97 may normally hold the handle 93 in an upwardly extended position, or, if desired, the bar 96 and 97 may be folded by forcing them past said dead center, to cause the handle 93 to move downwards flat against the top face of the body 90. At the rear of the flat body 90 there is a heel element 99 in which a skate-heel back may be placed. This scooter is intended to be of a small size so that an operator may rest one foot on the scooter and use the other foot to propel the same.

In Fig. 15 another form of steering mechanism has been disclosed which is very similar to the form illustrated in Fig. 12 but distinguishing in several respects. According to this form, 5 the steering post 77 has a radially extending bottom end portion 77^{aa} which is pivotally connected with links 77^{bb} in turn pivotally connected with the front ends of clamps 21^{bb}. These clamps are pivotally supported near their rear ends by pintle 10 rivets 21^{cc} upon the body of the disc 18. The clamps 21^{bb} support brackets in turn supporting traction elements such as the wheels 19.

In other respects this form of the invention is similar to the form illustrated in Fig. 12 and 15 like parts may be recognized by the same reference numerals.

When the steering wheel 82 is turned it will 20 turn the radial arm 77^{aa} which will turn in one direction or the other, and this motion will be transmitted by the link 77^{bb} to pivot the brackets 21^{bb} towards the right or towards the left, and so accomplish the steering.

While we have illustrated and described the 25 preferred embodiments of our invention, it is to be understood that we do not limit ourselves to the precise constructions herein disclosed and the right is reserved to all changes and modifications coming within the scope of the invention as defined in the appended claims.

30 Having thus described our invention, what we claim as new, and desire to secure by United States Letters Patent is:

1. A scooter, comprising a flat body, a disc 35 axially rotatively mounted on the bottom face of said body at its front end, traction elements mounted on the bottom of said disc, a member mounted on said disc and extending through an arcuate slot in said body coaxially of said disc, a handle hingedly mounted on said disc and extending upwards for steering the scooter and foldable upon said flat body, a base arm hingedly connected with said member, a front arm hingedly connected with said base arm and with said handle, and a latch for holding said arms fixedly 40 together.

2. A scooter, comprising a flat body, a disc 45 axially rotatively mounted on the bottom face of said body at its front end, traction elements mounted on the bottom of said disc, a member 50 mounted on said disc and extending through an arcuate slot in said body coaxially of said disc, a handle hingedly mounted on said disc and extending upwards for steering the scooter and foldable upon said flat body, a base arm hingedly 55 connected with said member, a front arm hingedly connected with said base arm and with said handle, and a latch for holding said arms fixedly together, and a reinforcement plate mounted upon the bottom of said flat body and superimposed upon said disc and having an arcuate slot 60 aligned with a slot in said disc, and a ball bearing interposed between said disc and said plate.

3. A scooter, comprising a flat body, a disc 65 axially rotatively mounted on the bottom face of said body at its front end, traction elements mounted on the bottom of said disc, a member 70 mounted on said disc and extending through an arcuate slot in said body coaxially of said disc, a handle hingedly mounted on said disc and extending upwards for steering the scooter and foldable upon said flat body, a base arm hingedly 75 connected with said member, a front arm hingedly connected with said base arm and with said handle, and a latch for holding said arms fixedly together, said member comprising an angle mem-

ber having one arm attached to said disc and having its other arm extended upwards through said slot.

4. A scooter, comprising a flat body, a disc 80 axially rotatively mounted on the bottom face of said body at its front end, traction elements mounted on the bottom of said disc, a member 85 mounted on said disc and extending through an arcuate slot in said body coaxially of said disc, a handle hingedly mounted on said disc and extending upwards for steering the scooter and foldable upon said flat body, a base arm hingedly connected with said member, a front arm hingedly connected with said base arm and with said handle, and a latch for holding said arms fixedly 90 together, said handle having a top horizontal portion by which it may be gripped and side portions extending downwards across the sides of said body, and a bottom portion extending across said disc and hingedly connected therewith. 95

5. A scooter, comprising a flat body, a disc 100 axially rotatively mounted on the bottom face of said body at its front end, traction elements mounted on the bottom of said disc, a member 105 mounted on said disc and extending through an arcuate slot in said body coaxially of said disc, a handle hingedly mounted on said disc and extending upwards for steering the scooter and foldable upon said flat body, a base arm hingedly connected with said member, a front arm hingedly connected with said base arm and with said handle, and a latch for holding said arms fixedly 110 together, said handle having a top horizontal portion by which it may be gripped and side portions extending downwards across the sides of said body, and a bottom portion extending across said disc and hingedly connected therewith, by several brackets mounted upon the disc. 115

6. A scooter, comprising a flat body, a disc 120 axially rotatively mounted on the bottom face of said body at its front end, traction elements mounted on the bottom of said disc, a member 125 mounted on said disc and extending through an arcuate slot in said body coaxially of said disc, a handle hingedly mounted on said disc and extending upwards for steering the scooter and foldable upon said flat body, a base arm hingedly connected with said member, a front arm hingedly connected with said base arm and with said handle, and a latch for holding said arms fixedly 130 together, said arms being of U-shape in transverse cross section and portions of said arms being set one into the other. 135

7. A scooter, comprising a flat body, a disc 140 axially rotatively mounted on the bottom face of said body at its front end, traction elements mounted on the bottom of said disc, a member 145 mounted on said disc and extending through an arcuate slot in said body coaxially of said disc, a handle hingedly mounted on said disc and extending upwards for steering the scooter and foldable upon said flat body, a base arm hingedly connected with said member, a front arm hingedly connected with said base arm and with said handle, and a latch for holding said arms fixedly 150 together, said arms being of U-shape in transverse cross section and portions of said arms being set one into the other, and said latch comprising a U-shaped spring mounted within one of the arms, locking pins mounted on the side arms of 155 said spring and engaged through the overlapping portion of said arms to lock them together, and another pin mounted on said side arms by which said side arms may be manipulated to release said locking pin. 160

8. A scooter, comprising a flat body, a disc axially rotatively mounted on the bottom face of said body at its front end, traction elements mounted on the bottom of said disc, a member mounted on said disc and extending through an arcuate slot in said body coaxially of said disc, a handle hingedly mounted on said disc and extending upwards for steering the scooter and foldable upon said flat body, a base arm hingedly connected with said member, a front arm connected with said base arm and hingedly connected with said handle, a latch for holding said arms fixedly together, and back wheels for said flat body.
9. A scooter, comprising a flat body, a disc axially rotatively mounted on the bottom face of
- 5 said body at its front end, traction elements mounted on the bottom of said disc, a member mounted on said disc and extending through an arcuate slot in said body coaxially of said disc, a handle hingedly mounted on said disc and extending upwards for steering the scooter and foldable upon said flat body, a base arm hingedly connected with said member, a front arm connected with said base arm and hingedly connected with said handle, a latch for holding said arms fixedly together, and a brake for said scooter.
